UNITED STATES PATENT OFFICE.

RICHARD D. GALLAGHER, OF CHICAGO, ILLINOIS.

GUARD RAIL AND MEANS OF APPLYING THE SAME.

Application filed April 17, 1922. Serial No. 554,219.

To all whom it may concern:

Be it known that I, RICHARD D. GALLAGHER, a citizen of the United States, residing at Chicago, in the county of Cook and State of Illinois, have invented certain new and useful Improvements in Guard Rails and Means of Applying the Same, of which the following is a specification.

My invention relates to guard rails and has particular reference to cast metal guard rails having lateral extensions such as tie plates, or similar means, cast integrally therewith, for passing under the track rails as means for fastening the guard rails in position against the track rails.

An object of the invention is to provide a guard rail with integral, lateral extensions, such as tie plates or the like, adapted for cooperation with wedging rail braces and blocks for securing the guard rails in position on the track rails.

Another object of the invention is to provide a guard rail having tie plates, or the like, integral therewith and wedging clamps cooperating with the tie plates, whereby the guard rail may be secured alongside a track rail without the agency of spikes and the like, if desired.

A further object of the invention is to improve guard rails for generally successful commercial manufacture and use.

Generally speaking, I carry out the preferred embodiment of the invention by forming a guard rail of cast metal having integrally formed lateral extensions, such as tie plates or similar members, adapted to underlie a track rail, which members cooperate with wedge blocks and braces similar to those described in my copending application, Serial No. 540,745.

The above recited and other objects will be apparent from the following description and drawings, and will be particularly pointed out in the appended claims.

In the drawings;

Figure 1 is an enlarged vertical transverse sectional view of one form of the invention.

Figure 2 is a top plan view of the guard rail of Figure 1.

Figure 3 is a top plan view, partially in section, showing certain details of construction.

Figure 4 is a view similar to Figure 1, showing a modification of the invention.

Figure 5 is a top plan view, with parts broken away, showing the application of the guard rail of Figure 4 to a track rail.

Figure 6 is a side elevation of a portion of the guard rail of Figure 4; and

Figure 7 is a transverse sectional view taken on line 7—7 of Figure 4.

Referring to Figures 1, 2 and 3, 10 is a standard T rail with which a guard rail A is associated. In this form of the invention the guard rail A is provided with a plurality of laterally extending members, such as tie plates 11 and 12, adapted to rest on the ties 13. In the drawings I have shown two tie plates but do not wish to be limited to two, as under certain circumstances it may be desirable to use more. The guard rail A is also provided with laterally extending, suitably spaced, abutments or lugs 14, which are adapted to rest against the web 15 of the rail 10, to maintain the guard rail A in proper position, and which also serve as elements cooperating with the clamps for securing the guard rail in position.

The outer ends of the tie plates 11 and 12 are provided with upstanding lugs or shoulders 16, as shown on the drawings. The tie plates 11 and 12 are provided with apertures 17, through which bolts 18 may pass. The wedge blocks and braces, which I employ for securing the guard rail A in position, include braces 19 and blocks 20. The braces 19 have heads 21 adapted to underlie the head of the rail 10 and rest on top of the flange of the rail, and also abut the rail web 15, as shown at 22. The braces 19 have elongated openings 23 therethrough for reception of the bolt 18. The braces also have inclined surfaces 24 and 25, which are parallel but in different planes, and which planes incline to the horizontal. The wedge blocks 20 are provided with elongated centrally disposed apertures 26 and with inclined surfaces 27 and 28 for cooperation with the surfaces 24 and 25 of the braces 19. The blocks 20 are adapted to rest against the shoulders 16 of the tie plates 11 and 12.

Referring to Figure 1 of the drawings, it will be noted that the guard rail A may be secured in position on the track rail 10 by placing the same on the inside of the track rail 10, as shown in Figure 2, with the tie plates resting on the ties 13. The outer ends 110

of the tie plates 11 and 12 are provided with recesses 29 for the reception of spikes to secure the tie plate to the tie, if desirable.

In the form shown, the guard rail is placed in position with the lugs 14 abutting the web 15 of the track rail 10. Bolts 18 are then inserted through the holes 17 in the tie plates, suitable counter-bores being provided in the tops of the ties for the reception of the bolts. The rail braces 19 are then applied over the bolt as are the wedge blocks 20, a nut 32 is then applied to the end of the bolt 18 and screwed home, thereby forcing the wedge block 20 against the shoulder 16 and consequently urging the rail brace 19 against the rail 10 for securely holding the guard rail A in position thereon. It will be noted that as the nut 32 is tightened, the wedging effect between the rail braces 19 and wedge blocks 20 is secured by reason of the cooperating inclined surfaces 24, 25, 27 and 28 of these elements, which act to force the guard rail against the track rail and clamp the guard rail thereto. Such construction prevents tilting of either rail, as each acts as a check for the other.

When it is desired to apply the guard rail without the use of spikes the ties 13 are then drilled with holes 30 from top to bottom and bolts 31 are inserted, which extend through the apertures 17, 23 and 26 in the tie plates, rail braces and blocks, respectively. If the bolt 30 were used in place of the bolt 18, this would pass through the tie 13 and through the rail brace 19 and wedge block 20 in the manner shown with respect to bolt 18.

In the form of invention shown in Figure 4 through 7 the guard rail B is provided with lateral extensions in the form of integral yokes 33 arranged to underlie the track rail 10 between adjacent ties. The yoke 33 is adapted to extend under the track rail and in the present instance is provided with an upturned end 35 offering a flat face 36 parallel to the rail 10. Rail braces 19 and wedge blocks 20 are employed and function in the same manner as described with reference to Figure 1. The web of the yoke 33 is provided with a vertically extending recess 37 formed by the walls 38 and 39 for receiving the bolt 40 which holds the rail brace 19 and wedge block 20 in position. A nut 41 cooperates with the bolt for the purpose of securely wedging the members 19 and 20 against the rail for fastening the guard rail B to the track rail 10. In the drawings in Figure 5 I have shown three such yokes 33, but do not wish to be limited to this number as more or fewer yokes may be employed as occasion demand. The web of the guard rail B is provided at suitable intervals with openings 42 so that ice, dirt and the like, which accumulates be-

tween the guard rail and track rail, may be discharged. The lateral flange 43 of the guard rail, if desired, may be provided with spike holes 44 so that the guard rail may be spiked to the ties 45, if desired, thus permitting its application without the use of the adjustable clamps and other features of this invention. However, I have found that the guard rail B may be suitably secured in position on the track rail 10 by the clamps 19 and 20 cooperating with the yokes 33, doing away with the use of any spikes whatsoever.

The manner of applying the guard rail is as follows:

Wherever it is desirable to apply the guard rail B alongside a portion of the track rail 10, it is done by placing the guard rail with the laterally extending yokes 33 passing under the track rail between adjacent ties, so that the outer ends of the yokes lie on the opposite side of the track rail from the guard rail. The bolts 40 are then inserted in the recesses 37, the rail braces 19 applied over the bolts and with the heads of the braces against the head and web of the track rail 10, as shown in the drawings. The wedge blocks 20 are then applied over the bolts with the inclined surfaces of the blocks in contact with the inclined surfaces of the braces and with the downturned ends of the blocks against the abutments or shoulders 16 in the arrangement of Figure 1 and shoulders 36 in Figure 4. The nuts 41 are then applied to the bolts and screwed home. This results in the blocks 20 being moved downwardly and by reason of the contact of the same with the shoulders 16 or 36, bodily displacement of the same is prevented. The braces 19, by reason of the inclined surfaces of the same being in contact with the inclined surfaces of the blocks 20, are caused to move towards the rail, clamping the rail firmly, or in other words, moving the yokes 33 so as to clamp the guard rail B securely against the track rail 10. The nuts 41 are manipulated until all of the adjustable wedge clamps are secured and the guard rail B is immovably associated with the track rail. It will be noted that the guard rail is clamped against the track rail in such manner as to prevent tilting either of the guard rail or track rail and that the guard rail is held in position without the use of spikes.

At each end of the guard rail I provide laterally extending portions 46, positioned in such manner as to prevent any person from catching his foot between the guard and track rails.

While I have described more or less precisely the details of construction of my invention, I do not wish to be understood as limiting myself thereto, as I contemplate

changes in form and proportion of parts, and the substitution of equivalents as circumstances may suggest or render expedient, without departing from the spirit of my invention.

I claim:

1. A guard rail of cast metal having tie plates formed integrally therewith, wedge blocks cooperating with said plates for securing said guard rail to a track rail, said wedge blocks having a plurality of parallel surfaces inclined to the horizontal, and means for effecting movement of said blocks for wedging purposes.

15 2. A guard rail of cast metal having tie plates or the like formed integrally therewith, said plates adapted to underlie a track rail, shoulders formed at the ends of said plates, and wedge means for securing said 20 guard rail to a track rail, said means including a brace adapted to abut the track rail and a wedge block cooperating with said brace adapted to abut said shoulders, said block and brace having a plurality of cooperating inclined wedging surfaces, and means for actuating said block to effect 25 clamping engagement of the parts.

3. A guard rail having members integrally formed therewith adapted to underlie 30 a track rail, and clamping members cooperating with the outer ends of said members for securing said guard rail in position on a track rail, said clamping members having a plurality of surfaces inclined to the horizontal and in different parallel planes.

35 4. A guard rail having members integrally formed therewith adapted to extend beneath a track rail, abutments on the ends of said members, clamping members including a rail brace and a wedge block cooperating with said abutments for securing

said guard rail in clamped position on a track rail, said guard rail having lugs for positioning the same with respect to the track rail for the purpose of maintaining 45 clearance for the wheel flanges.

5. A cast metal guard rail having lateral extensions for extending under track rails, the ends of said extensions being provided with abutments, bolts passing through said 50 extensions near said abutments, members cooperating with said abutments and said bolts for effecting wedging action between said abutments and the track rail for clamping the guard rail thereagainst, and means 55 cooperating with said bolts for effecting wedging action of said members.

6. A guard rail of cast metal having laterally extending members integral therewith adapted to extend underneath a track 60 rail, said extensions having abutments near the outer ends thereof, wedge means cooperating with said abutments for clamping said guard rail to a track rail, said wedge means including a rail brace for contacting 65 a portion of the track rail on the side opposite the guard rail, said brace having a pair of inclined surfaces which are parallel and in different planes which planes are inclined to the horizontal, a wedge block also having 70 a pair of similarly inclined and positioned surfaces for coacting with said brace surfaces, said block adapted to rest against the said abutments, and means for drawing said block downwardly to force said brace and 75 said abutments apart for clamping said guard rail to said track rail, said guard rail being provided with stops to limit the movement of the same towards the track rail.

Signed at Chicago, Illinois, this 14th day 80 of April, 1922.

RICHARD D. GALLAGHER.
